SMOKING PIPE
Henry Paul, Jr., 212 Jane St., Weehawken, N.J.
Filed Feb. 7, 1964, Ser. No. 343,305
2 Claims. (Cl. 131—176)

The present invention relates to smoking tobacco pipes, and more particularly to the type in which the tobacco is adapted to be burned from the bottom up, rather than from the top down.

A primary object of the invention is to provide an improved smoking pipe of the aforementioned type which comprises improved means for the prevention of distillation of nicotine or other harmful tars while simultaneously precluding the conveyance of saliva to the tobacco or the return thereof to the mouth, thus preventing any tobacco tongue bite.

Another object is to provide an improved pipe according to the preceding objective in which there is provided under draft means in combination with conduit means forming an overhead and down-draft means adjacent to and in communication with the bowl and in operative communication with the conventional stem bore, which prevents the formation of any soggy heel or hard core of tobacco, thus effectively facilitating the complete combustion of said tobacco, providing more enjoyable smoking with relatively little or minimal cleaning thereof required.

Still another object is to provide novel yieldable and pivotable base cover means in combination with the bowl of the pipe to facilitate easier and more efficient loading, lighting and burning, and cleaning thereof with the attendant advantages of safety and fire preventiveness by precluding the emission of any sparks whether the pipe is inadvertently spilled, placed upon furniture, or put into the user's pocket while containing a burning charge of tobacco, in addition to providing a very satisfying and palatable smoke even when subjected to severe rainy or windy weather conditions.

These and other objects, such as the provision of a compact, durable, yet readily manipulatable pipe bowl and cover structure which is attractive in appearance and relatively inexpensive to manufacture, will become more apparent from the following detailed description taken in conjunction with the accompanying illustrative drawing figures, in which

FIGURE 1 is a longitudinal cross-sectional view of my improved pipe;

FIGURE 2 is a bottom plan view of the pipe of FIGURE 1;

FIGURE 3 is a detailed exploded composite sectional and side elevational view of the structural elements of my improved pipe; and

FIGURE 4 is a partial side elevational view, with parts shown in section and illustrating a modification of the device.

Referring now to the drawings, wherein like reference characters designate corresponding parts throughout the several figures of the drawing, A designates the pipe generally, having a downwardly opening bowl B, a base cover C and a stem S.

More specifically, the bowl B, made preferably of briar, comprises a generally barrel-shaped, combustion chamber 10 with a vertically disposed axis and defined by cylindrical and generally vertically disposed side walls 12 and a top flattened wall 14, said chamber 10 or bowl having an open bottom rim or mouth 16 which is adapted to be closed by said base cover means C during use.

The stem S comprises a composite shank including a portion 18 formed preferably integral with and attached at about the mid-point of the bowl between its top 14

2

and bottom cover C, and a detachable stem portion 20 terminating in a conventional open-ended mouth piece 22. The stem S is provided with the usual horizontal longitudinal conduit 24 communicating with the chamber 10 by means of a transverse and vertically disposed connecting conduit or flue channel 26. The channel 26, which serves as the down-draft flue, is arranged in spaced relation and generally parallel to the bowl's combustion chamber 10 as shown in FIGURE 1, and includes an enlarged area or counterbore 28 which is drilled or otherwise suitably formed therein from the bottom rim 16. Said counterbore 28 preferably extends above the intersection of stem conduit 24 to provide a combined miniature expansion and cooling chamber for the smoke during its travel through the conduits 26 and 24.

The counterbore area 28 immediately above the intersection of conduit 24 is used to provide a moisture collecting trap 30, and is further used to house the cover's pivotal and axially yieldable anchor means 32, to be described in detail hereinafter.

The cover C is provided with a metallic or ceramic shield 34 or fire resistant liner secured thereto as by means of a recessed rivet 36 or the like, to provide several shielding functions. The cover is adapted to be first yieldably extended away from the rim 16 to clear said shield and then pivotally rotated about the anchor means 32 to provide access for filling with tobacco, igniting and subsequently cleaning said bowl. The anchor means, 32, as shown, comprises a fastener such as a screw 38, an expansion spring 40, a bearing sleeve 42 having shouldered seat 43, and a fastener-securing insert or screw anchor 44 having complementary internal threads to accommodate the threaded shank of said screw 38 whose head is provided with an enlarged slot, all of which are more clearly shown in exploded fashion in FIGURE 3.

The screw anchor or tapped insert 44 is either externally threaded to mate with threads 46 provided in counterbore 28, or it may have a knurled outer surface and be press-fit within the bore, to a distance spaced below the intersection of stem conduit 24 and counterbore 28, to provide the aforementioned moisture trap 30 thereabove. Cover C is provided with a bore 48 in axial alignment with the counterbore 28 in the rim, in which the shouldered bushing or bearing sleeve 42 is adapted to be recessed, and the latter, in turn, being adapted to receive both the spring 40, against its shouldered seat 43, and screw 38 as shown in FIGURE 1 when assembled.

The outer or front wall 12 of the bowl may be provided with a plurality of spaced air inlet apertures 50 adjacent the lower rim area 16, as for example five or six have been found to provide a very satisfying, cooler smoke than conventional pipes. Said apertures 50 may be selectively covered or uncovered to suit the individual's desires, as by covering or uncovering the same with one's finger.

The illustration of FIGURE 4 shows a modification of the cover, anchor means, and cleaning access structures of the precedingly described exemplification. As shown therein, the modified cover eliminates the need of bore 48 and substitutes therefor a hinge 52. The hinge is secured to the respective parts by wood screws or other suitable fastening means. The modified anchor means eliminates the need of spring 40. The sleeve 42 is placed in the lower portion of the bore 28 and serves to position and retain the headed end of the screw 38, the underside of the cover C being recessed as shown, to accommodate the head of the screw. The cover includes a recessed portion 54 and the bowl includes a matching protruding portion 56 having a detent on an inner surface thereof. The cover includes a spring loaded catch 58 for retaining the cover in its closed position.

Small force is required on the cover to disengage the catch from the detent and lower the cover on hinge 52.

The phantom line drawing of cover C illustrated this lowered position and shows more clearly the relative position afforded the elements by such movement.

The function of shield 34 is two fold: First, it prevents burning particles of tobacco from dropping and possibly escaping from apertures 50; second, it collects products of combustion by virtue of its shape which otherwise would collect on the cover and interfere with its tight closing; and third, it protects the cover from charring when the pipe is first lit.

The operation will now be summarized as follows: The pipe is inverted to place the combustion chamber or bowl with the open side upward. In the exemplification of FIGURE 1, the base cover C is yieldably pulled in an axial direction away from the rim 16 of the bowl against the pull of spring 40, a sufficient distance to clear the concave shield 34, then rotated to the side about the pivotal axis of the mounting screw and bushing 38 and 42 respectively, to expose the bowl for charging. After the charge of tobacco has been inserted, it is initially ignited in this same inverted position and subsequently the base cover C is again axially pulled out and returned to its place with respect to the vertical axis of the bowl, and then the pipe is returned to its normal upright position, whereupon the ignited charge of tobacco is supported by the bowl and the air inlets or apertures 50 assure continued combustion of the tobacco as it burns from the bottom upwardly, with the smoke being down drafted through the conduit 26 prior to passage through the stem; conduit 24, thus together with trap 30, reducing the passage to the mouth of juices which may be distilled during combustion.

The operation of the modification of FIGURE 4 differs from the above only in the manner in which the cover is opened and closed. A small lifting force on the cover disengages spring catch 58 from the detent in portion 56 and allows the cover to pivot to the phantom line position. Filling and lighting is then accomplished before the cover is returned to the closed position and the catch engages the detent.

Cleaning of this improved pipe is facilitated by simply removing the base cover as a unit, by turning said screw with a coin or small tool, thus permitting passage of a pipe cleaner in through conduits 28 and 26 to the bowl chamber 10.

From the foregoing, it is apparent that an improved pipe has been evolved which fulfills the objects and advantages as set forth in the preamble of this specification.

While specific details have been shown and described other changes and modifications may be made, such as

providing suitable combustion air apertures in the base cover rather than in the rim, or the provision of a cover having a concave and fire-resistant lining shield formed integrally therewith, without departing from the spirit and scope of the invention as defined in the appended claims.

What is claimed is:

1. A tobacco smoking pipe adapted for bottom up burning of tobacco, comprising in combination a bowl having a vertical axis and including a combustion chamber having a closed top and an open base end, a stem connected to said bowl portion and having a smoke conduit in operative communication with said combustion chamber, a base-end-mounted cover having an inner and outer face for enclosing the combustion chamber, an anchoring means disposed in conjunction with said cover and bowl, said cover anchoring means comprising a fastener securing means provided in said bowl portion adjacent the combustion chamber, a bearing sleeve carried by said cover and having a shouldered seat portion and disposed within aligned apertures formed in said cover and bowl portions, a removable fastener element having an enlarged head end extending through said bearing sleeve disposed in said cover with the head end disposed adjacent the outer face of said cover, with its other end adapted for cooperation with said fastener securing means aforesaid, and yieldable means interposed between the headed end of said fastener element and the shouldered seat portion of said bearing sleeve.

2. A tobacco smoking pipe as defined in claim 1 wherein the yieldable means interposed between the headed end of the fastener and the bearing seat is a spring.
